ATTORNEY.

UNITED STATES PATENT OFFICE.

CHARLES E. JOHNSON, OF PILLAGER, MINNESOTA.

SCREENING MACHINE.

Application filed July 5, 1921. Serial No. 482,468.

To all whom it may concern:

Be it known that I, CHARLES E. JOHNSON, a citizen of the United States, residing at Pillager, in the county of Cass and State of Minnesota, have invented a new and useful 5 Screening Machine, of which the following is a specification.

This invention relates to machines which may be used to sort potatoes of different 10 sizes as they are taken from the field and to separate the same from other dug material such as earth and stones.

The invention has for an object to provide 15 for the separation of potatoes from other dug material during the travel of the potatoes up and over an inclined cribble or screen mounted on a trough, those potatoes which do not pass thru the cribble being carried up to the end of the trough where they 20 are discharged into a spout which directs the potatoes to one side or the other of the machine, while those passing through the cribble are further sorted on another screen immediately below the first, the matter 25 which passes through the second mentioned screen being received on a shelf or chute which conducts it to one side of the machine, the second mentioned screen extending beyond the chute so that objects or matter dis- 30 charging from the shelf or chute and screen will not mingle in a common heap and so that receptacles may be more conveniently placed at the discharge end of the chute and screen without mutual interference.

35 Referring now to the drawings in which the preferred form of the invention is shown,—

Fig. 1 is a plan view of the screening machine;

40 Fig. 2 is a side elevation of the same;

Fig. 3 is an end elevation of the machine viewed from the right of Fig. 2;

45 Fig. 4 is a side elevation on an enlarged scale of a portion of the machine showing the screen arrangement;

Fig. 5 is a vertical section taken thru the device shown in Fig. 4;

50 Fig. 6 is an end elevation on an enlarged scale of the upper end of the chute showing how the spout may be supported in either of two positions, and

Fig. 7 is a fragmentary detail in side ele-

vation showing how the spout of Fig. 6 is removably connected to the side walls of the chute.

55 In the drawings like characters of reference indicate like parts throughout the several views.

10 indicates a chute or trough supported in inclined position on any suitable frame 60 such as standards 11. For convenience in transporting the machine, runners or skids 12 may be secured to the lower ends of the standards and at the ends of the runners suitable draft connections 13 may be provided.

65 Arranged at either end of the trough or chute 10 is a sprocket wheel or the like 14. Looped over these wheels is an endless flexible conveyer 15 having cross slats 16 secured 70 thereto for carrying material from one end of the chute to the other as will be readily understood.

75 The flexible conveyer may be actuated in any suitable manner. For convenience of illustration, there is indicated a hand crank 17 to which is secured a sprocket wheel 18 which is suitably mounted on the side wall of the chute. Passing over this wheel is a belt 19 which likewise passes over a sprocket 20 affixed to a shaft 21 on which the sprocket (not shown) corresponding to the sprocket 14 is affixed. Also affixed to this shaft is a belt pulley 22 to enable the flexible conveyer to be driven by mechanical power if so desired.

80 At the lower end of the chute 10 is a hopper 23 into which the potatoes and other dug material are shoveled. This hopper has a slot 24 therein through which the slats 16 of the flexible conveyer pass upwardly during the operation of the machine. In order to prevent material from falling thru the slot immediately after a slat has passed therethru, there is provided any suitable trap such as a flexible leather flap 25 secured to the hopper adjacent the slot. This flap will normally overlie the slot but will be pushed aside by the slat after the latter comes thru the slot as will be readily understood.

85 Arranged at the upper end of the chute 10 is a spout 26. This spout is detachably secured to one or the other of the side walls

of the chute and extends downwardly and transversely of the same whereby the material received into the spout is discharged at one side or the other of the machine. As shown more fully in Figs. 6 and 7, the spout 26 is secured to the side wall 10^a of the chute 10 by means of two buttons 27 which enter a pair of keyhole slots 28 in the spout.

In order to allow the upper end of the spout to extend outwardly or beyond the end of the chute a sufficient distance to enable the potatoes carried up by the conveyer to be dumped and retained thereon, it is desirable that three or more key-hole slots 28 be provided in the upper end of the spout. In transferring the spout from one side to the other of the chute, that key-hole slot adjacent the edge of the spout most remote from the chute will, of course, not be used, as will be readily understood. The spout is supported at its lower end by means of a rod 29 which at its upper end is secured to one of the buttons 27 and at its lower end is hooked into a perforation 30 in the remote side wall 25 of the chute. The other side wall is also provided with a similar perforation which will receive the hooked end of the rod when the spout is transferred to the other side of the chute. This supporting of the spout by a rod which extends across the same to the remote side thereof, not only holds up the discharge end of the spout, but also prevents the outer half thereof from buckling or bending, due to the fact that a portion 30 of the upper end of the spout extends beyond and is unsupported by the buttons.

The spout, it will be noted, underlies the upper loop of the flexible conveyer and is so disposed that material carried up by the conveyer falls thereon. The frame which supports the chute 10 is high enough and the spout 26 is of such length as to enable the latter to discharge directly into a wagon box.

The mechanism for screening and grading the potatoes will now be described. Intermediate the ends of the chute is a cribble or screen 31 which is arranged across an opening in the bottom of the chute. This screen is preferably supported on a plurality of longitudinally extending strips 32 which are suitably secured to the bottom of the chute. Disposed over the screen are, likewise, a plurality of strips 33 which serve to form a support for the conveyer slats 16 as they pass over the screen.

Depending from the chute 10, below the screen 31, is a frame 34 having a pair of inwardly and laterally extending shelves or ledges 35 for supporting a screen 36. The frame 34 preferably has a closed back 34^a from which the screen 36 extends to a point at one side of the machine. This screen 36 is preferably dished into the form of a spout so that the material received thereon and

not passing therethru will roll down to the lowest parts of the same and eventually leave it in a well defined path. The screen serves, therefore, not only to sift material falling thereon, but also as a discharge spout for material which remains thereon.

In order that material passing thru the screen 36 may be collected at a definite point, the frame 34 is preferably closed at its bottom as at 34^b to form an inclined shelf down which the material received from said screen may pass. This shelf preferably terminates short of the terminus of the screen 36 so as not to confuse the materials leaving the screen 36 and said inclined shelf. It is contemplated that suitable receptacles will be placed beneath said screen and shelf to receive the materials discharged therefrom.

The cribble 31 is designed to be removably secured in the chute 10. Realization of this object is obtained by cutting out a gate-way 10^b in the side wall of the chute as indicated in Fig. 4 and supporting the cribble between the lower and upper strips 32 and 33 respectively. Inasmuch as the cross bars or slats 16 of the flexible conveyer do not contact directly with the screen but rest on the slats 33, the screen 31 may be readily withdrawn without interference with said conveyer. The cribble is secured against lateral displacement by any suitable means such as turn buttons 37. The second screen 36 may also be removed and replaced by a screen of different mesh and is retained in place on its ledges 35 in any suitable manner.

The mode of operation of the machine will now be clear. After the potatoes are shoveled into the hopper 23 and are moved up the chute by means of the flexible conveyer, some potatoes and earth, sand and ground will pass thru the cribble 31 and fall upon the under-lying screen 36, the larger potatoes, however, being carried upward by the conveyer and dumped into the spout 26 to be discharged into a suitable receptacle such as a wagon box. Of the material and potatoes falling on the screen 36 some will pass thru and some not. That which does not pass thru will roll down the screen and be spouted ed therefrom and that falling on the shelf 34^b will likewise be discharged therefrom.

Suitable means 37 for supporting a sack may be secured to the terminals of the ledges 35. Various other details may be provided without departing from the spirit of the invention.

While the invention has been described with considerable particularity of detail, reference is to be had to the appended claims for the scope of the invention.

What I claim is:

1. In a screening machine, the combination of an inclined trough having a cribble in its bottom and an endless flexible conveyor for moving material over the cribble,

a frame depending from the trough below the cribble, a chute at the bottom of the frame, and an inclined screen interposed between the cribble and chute, the discharge 5 end of the screen extending beyond the like end of the chute.

2. In a screening machine the combination of an inclined trough having a cribble in its bottom and an endless flexible 10 conveyor for moving material over the cribble,

a frame depending from the trough below the cribble, an inclined shelf at the bottom of the frame and a spout-like screen supported by said frame intermediate the cribble and shelf, the discharge end of the screen 15 extending laterally further from the trough than the like end of the shelf.

In testimony whereof I have hereunto set my hand this 27th day of June, 1921.

CHARLES E. JOHNSON.
